LOOSE LEAF BINDER

Stanley G. Johnson, Grosse Pointe, Mich., assignor to The Burkhardt Company, a corporation of Michigan

Application May 4, 1934, Serial No. 723,944

6 Claims. (Cl. 129—13)

This invention relates to loose leaf binders of the post type and is applicable to both closed back and open back binders.

The main object of this invention is to provide a sturdy inexpensive binder of such construction that the leaf-engaging members may be positively locked in compressed or any desired relation to each other.

Another object of this invention is to provide 10 a loose leaf binder having post type locking devices secured to one of the leaf-engaging members capable of positively biting into cooperating posts secured to the other leaf-engaging member to positively hold the said leaf-engaging members 15 in compressed or any desired relation to each other.

Another object of this invention is to provide 20 a positive locking post type loose leaf binder which may be economically but sturdily constructed with screw machined post type locking device parts as distinguished from the usual well known stamped guides and slides which may be easily bent out of alignment during use.

And still another object of this invention is 25 to provide a positive vise-like biting engagement between the cooperating parts of the locking device which holds the leaf-engaging members in the desired relation to each other as distinguished from the usual frictional type locking devices.

An illustrative embodiment of this invention as applied to a closed back binder is shown in the accompanying drawing, in which:

Fig. 1 is a view in perspective having portions 35 of the binder broken away showing a loose leaf binder of a construction embodying the invention.

Fig. 2 is an enlarged transverse section of Fig. 1 showing the binder unlocked and the cooperating parts of the binder and locking device disengaged.

Fig. 3 is an enlarged cross sectional view similar to Fig. 2 except that the binder is in a locked position and the cooperating parts of the binder 45 and locking device are shown engaged.

Fig. 4 is a vertical section taken on line 4—4 of Fig. 2.

Fig. 5 is a vertical section taken on line 5—5 of Fig. 3.

Fig. 6 is a sectional view taken on line 6—6 of Fig. 3 looking in the direction indicated by the arrows.

Fig. 7 is a detailed view in perspective showing the vise-like biting engagement between the co-operating parts of the locking device.

In the embodiment of the invention shown in the drawing the loose leaf binder comprises two leaf-engaging members 10 and 11 disposed in opposite relation to each other, covers 12 and 13 flexibly connected or hinged to the said leaf-engaging members, solid and hollow posts 14 and 15 on leaf-engaging members 10 and 11 respectively capable of receiving punched filler sheets 16 by means of properly spaced holes therein, and two hollow post type locking devices having preferably hardened solid posts 17 on one of the leaf-engaging members 10 and hollow posts 18 on the other leaf-engaging member 11.

The solid and hollow posts 14, 15, 17 and 18 may be arranged in any desirable staggered relation with respect to the leaf-engaging members 10 and 11. The leaf-engaging members 10 and 11 are each preferably formed of sheet metal in the shape of an L to provide a closed back for the binder. However, they may each comprise simply a flat sheet of metal for the open back type of binder. The leaf-engaging members, covers, flexible cover connections or hinges and covering for the same may be of any desired construction and material known in the bookbinding art.

This invention consists of a novel means for positively locking the leaf-engaging members of a post type loose leaf binder in a compressed or any other desired relation to each other within the useful limits of the telescoping engagement of the solid and hollow posts thereof. The locking means relies upon a vise-like grip and a biting engagement between the cooperating parts of the locking device.

The said locking device consists of a round solid post 17 preferably having an upset and shouldered hollow end forming a rivet 19 for securing the said post to the leaf-engaging member 10, the said solid post 17 being preferably identical in size and detail as solid posts 14. A hollow post 18 having an internal diameter slightly larger than solid post 17 being preferably shouldered to form a rivet 20 for securing the same to the leaf-engaging member 11, the said hollow post 18 is preferably equal in height and internal diameter to hollow posts 15.

Solid posts 14 and 17 are riveted or otherwise secured to the leaf-engaging member 10 at such spacing that they will register with and be 50 telescopingly engaged by hollow posts 15 and 18 which are riveted or otherwise secured to the leaf-engaging member 11.

The hollow posts 18 are preferably formed by drilling an eccentrically located vertical hole 55

slightly larger in diameter than the solid posts 17 through a round blank of the proper length, flattening the remaining thick wall of the post to form a flat side of the said post 18 as shown in Fig. 1, and shouldering the same to form a hollow rivet at the bottom thereof as hereinbefore described.

Now referring to Fig. 6, each hollow post 18 is provided with a horizontally disposed round hole 21 drilled normal to the flat side of and partly through the hollow post 18 and on the same center as a smaller hole 22 which forms a shoulder 23 to seat a preferably hardened locking member 24 which functions to lock the solid post 17 against movement relative to the hollow post 18 when telescopingly engaged thereby.

The locking member 24 is formed with a shoulder beneath its head 25 to abut against the shoulder 23 formed in the hollow post 18. The head 25 of the locking member 24 is of slightly less diameter than the hole 21 to permit assembly and the free rotation of the locking member 24. The top of the head 25 of the locking member 24 is ground before hardening to form a concaved groove having substantially the same radius as the vertical hole in the hollow post 18. The shank of the locking member 24 is long enough to extend through the hole 22 in the hollow post 18, receive a spring washer 26, be flattened on two sides to provide a key 29 to engage an operating lever 30, and form a head to retain the said locking member, spring washer and operating lever in the desired position in relation to the said hollow post 18.

The locking member 24 may be tapered instead of shouldered without departing from the broad invention described herein, in which case holes 21 and 22 of the hollow post 18 would be formed as one tapered hole.

The operating lever 30 is provided with a lug 31 to abut against the hollow post 18 when the concaved head 25 of the locking member 24 is in a disengaged position in relation to the solid post 17 as shown in Fig. 2 and Fig. 4.

In operating the embodiment of this invention as illustrated in the drawing, the punched filler sheets 16 are inserted in the binder in registry with hollow posts 15 as shown in Fig. 1. The sheets 16 as indicated by the dotted lines in Fig. 2 may be stacked higher than hollow posts 15 and as high as desired within the useful limits of the telescoping engagement of the solid and hollow posts 17 and 18 of the locking devices.

The operating lever 30 is moved to the disengaged position shown in Fig. 2, the solid posts 14 and 17 are then brought in telescopic engagement with the hollow posts 15 and 18 respectively, the leaf-engaging members 10 and 11 are then preferably pressed into compressed relationship to each other thereby engaging the punched filler sheets 16 as in Fig. 3 and the operating lever 30 is moved to the engaged position as shown in Fig. 3 to lock the leaf-engaging members 10 and 11 in the desired relation to each other.

The positive locking means of engagement between the solid and hollow posts 17 and 18 is accomplished by the vise-like biting engagement therebetween as illustrated in Figs. 4, 5 and 7. Fig. 4 shows the solid and hollow posts 17 and 18 in unlocked relation to each other with the operating lever 30 in a disengaged position and the grooved head 25 of the locking member 24 coincident with the inner surface of the hollow post 18. When the operating lever 30 is moved

toward its engaged position it causes the grooved head 25 of the locking member 24 to turn thereby urging the solid post 17 against the inside of the hollow post 18 as indicated in Fig. 5; and by using the inside of the hollow post 18 to react against, a slight additional pressure on the operating lever 30 causes the high portions of the grooved head 25 of the locking member 24 to bite or cut into the solid post 17 thereby completing the positive locking engagement between the solid 10 and hollow posts 17 and 18.

It is readily observed that the above described binder is simple to operate, sturdy in construction and economical to manufacture, and provides an absolutely positive means for maintaining the 15 leaf-engaging members in any desired relation to each other.

Although only one form of this invention has been illustrated and described in detail, it will be apparent to those skilled in the art that various modifications may be made without departing from the scope of the appended claims.

I claim:

1. In a post type loose leaf binder having opposed leaf-engaging members and means for receiving 25 punched filler sheets, round solid posts secured to one of the leaf-engaging members, hollow posts having an internal diameter slightly larger than said round solid posts secured to the other leaf-engaging member telescopingly receiving said solid 30 posts, said hollow posts having radially disposed concentric apertures therethrough forming a shouldered recess within said hollow posts for receiving a locking member, a rotatable locking member having a head concaved substantially coincident with the inner surface of the said hollow posts within each of said hollow posts, the said locking members adapted to be urged into vise-like biting engagement with the said solid posts.

2. In a post type loose leaf binder having opposed leaf-engaging members and means for receiving punched filler sheets, solid round posts secured to one of the leaf-engaging members, hollow posts having an internal diameter slightly larger than said solid posts secured to the other leaf-engaging member adapted to telescopingly cooperate with said solid posts, said hollow posts having radially disposed concentric apertures therethrough forming a shouldered recess within said hollow posts for receiving a locking member, a locking member rotatably mounted within said hollow posts having head concaved substantially coincident with the inner surface of said hollow posts, and means to rotate said locking member to urge the solid post against the inside of the 55 hollow post and cause the high portions of the concaved head of the locking member to bite or cut into the said solid post.

3. A loose leaf binder comprising opposed leaf-engaging members, means on said leaf-engaging 60 members for receiving punched filler sheets, round solid posts secured to one leaf-engaging member, hollow posts having an internal diameter slightly larger than said round solid posts secured to the other leaf-engaging member telescopingly receiving said round solid posts, said hollow posts having radially disposed concentric apertures therethrough forming a shouldered recess within said hollow posts for receiving a locking member, a rotatable locking member within each of said 65 hollow posts having a head concaved substantially the same radius as the inside of said hollow posts, and means to rotate said locking members to cause the same to grip said solid posts with a vise-like biting engagement.

4. A loose leaf binder comprising leaf-engaging members, means on said leaf-engaging members for receiving punched filler sheets, solid round posts secured to one leaf-engaging member, 5 cooperating hollow posts having an internal diameter slightly larger than said round solid posts secured to the other leaf-engaging member, said hollow posts having radially disposed concentric apertures therethrough forming a shouldered recess within said hollow posts for receiving a locking member, a rotatable locking member within each of said hollow posts having a head concaved substantially the same radius as the inside of said hollow posts, means to rotate said locking member in one direction to cause the high portions of the concaved head of said locking member to bite or cut into positive engagement with said solid post, and means to limit the rotation of said locking member in the other direction to bring its concaved head into axial alignment with the said hollow post to permit free reciprocating movement of the solid post within the said hollow post. 10
5. In a post type loose leaf binder having opposed leaf-engaging members and means for receiving punched filler sheets, round solid posts secured to one of the leaf-engaging members, hollow posts having an internal diameter slightly larger than said round solid posts secured to the other leaf-engaging member telescopingly receiving said solid posts, said hollow posts having radially disposed concentric apertures therethrough forming a shouldered recess within said hollow posts for receiving a locking member, a rotatable locking member having a hardened head concaved substantially coincident with the inner surface of the said hollow posts within each of said hollow posts, the said locking members adapted to be urged into vise-like biting engagement with the said solid posts. 15
6. In a post type loose leaf binder having opposed leaf-engaging members and means for receiving punched filler sheets, solid round posts secured to one of the leaf-engaging members, hollow posts having an internal diameter slightly larger than said solid posts secured to the other leaf-engaging member adapted to telescopingly cooperate with said solid posts, said hollow posts having radially disposed concentric apertures therethrough forming a shouldered recess within said hollow posts for receiving a locking member, a locking member rotatably mounted within said hollow posts having a hardened head concaved substantially coincident with the inner surface of said hollow posts, and means to rotate said locking member to urge the solid post against the inside of the hollow post and cause the high portions of the hardened concaved head of the locking member to bite or cut into the said solid post. 20
